UNITED STATES PATENT OFFICE.

EDGAR E. GREVE, OF BELLEVUE, PENNSYLVANIA.

MAKE-UP POST FOR ROTARY-DRILLING APPARATUS.

Application filed February 28, 1923. Serial No. 621,795.

To all whom it may concern:

Be it known that I, EDGAR E. GREVE, a citizen of the United States, residing at Bellevue, in the county of Allegheny and State of Pennsylvania, have invented certain new and useful Improvements in Make-Up Posts for Rotary-Drilling Apparatus, of which the following is a specification.

This invention is for means for a make-up 10 tong post for use in connection with rotary well drilling apparatus.

In the art of rotary well drilling, the modern rotary is so constructed that the part thereof which holds the pipe or drill stem in suspension may be held stationary, while another part, called the gear ring, is rotated. In adding a section of pipe to a drill stem, that is, in making up a joint, a tong attached to the section of pipe to be added is rotated 20 by engagement with a post on the gear ring, while the drill stem is held against movement. The sections of drill pipe are generally provided with threaded box and pin connections, and when motion is transmitted to 25 the tong by the post, one section is screwed into the other. If the rotary is not stopped the instant the thread is taken up, the tong is liable to be damaged or damage result to some other part of the apparatus.

30 The present invention has for its principal object to provide a yieldable means between the tong and the table having sufficient resistance to transmit motion to the tong under normal circumstances, but which 35 will yield or release the tong when the thread is taken up.

The invention may be readily understood by reference to the accompanying drawings, in which:

40 Fig. 1 represents a side elevation of a preferred form of the invention applied to a rotary;

Fig. 2 is a side elevation of another form of the invention;

45 Fig. 3 is a similar view of still another modification;

Fig. 4 is a similar view of still another form of the invention.

50 Referring to Fig. 1 of the drawings, A designates a rotary of a suitable kind, and is only diagrammatically shown. Carried on the gear ring of the rotary is the make-up post 5.

Instead of being formed as a single 55 straight bar, the upper end of the post is bifurcated and through the bifurcated end

is a pin or bolt 6 which serves to pivotally support a bell crank lever 7 having a vertically extending tong engaging arm 8 and a downwardly curved arm 9.

The post 5 is slotted at 10 and passing through the slot is a rod 11 having one end thereof attached to the curved arm 9 of the lever. A compression spring 12 surrounds the other end of the rod and is confined between the post and a washer 13 on the end of the rod. The inner end of the spring preferably bears against a block 14 having a spherical seat in the post. The effective tension of the spring may be varied by adjusting nut 13^a on the end of the rod.

In Fig. 1 of the drawing, B designates the end of a pipe tong in engagement with the upper arm 8 of the lever. This is the usual relation of the parts in the operation 75 of screwing up a section of drill stem. The resistance of spring 12 normally holds the parts in this position. When, however, the threads have been taken up, the resistance of the tong to further movement overcomes the 80 pressure of the spring, and the lever rocks backwardly, as indicated by the dotted lines of Fig. 1, allowing the post to move on past the wrench. Breakage or injury to parts is thus avoided.

A compression spring 15 around the rod 11 is preferably provided to cushion the return movement of the lever when it springs back to normal position.

In the form of the device shown in Fig. 2, 90 the post 20 carries a pivotally supported tong engaging member 21 pivotally supported at 22. A leaf spring 23 secured to the post, in any suitable way, as by clamp 24, has its free end bearing against the lever 95 21 to resist movement when turning the tong. When the resistance of the tong to turning becomes too great, however, the lever will rock back and allow the post to ride past the tong, as described in connection with Fig. 1. 100

In the device shown in Fig. 3, a bell crank lever 25 is pivotally supported at the top of the post as in Fig. 1, the lever having a normally vertical tong engaging arm 26 and a normally horizontal arm 27. The tong 105 engaging arm 26 may have a tong engaging plate 28 clamped thereto, preferably in such manner that it may be adjusted vertically.

The horizontal arm is preferably provided with a series of holes 29 therein. Secured to the post is an arm 30 having a vertically slidable rod 31 passed through a slot 110

therein. The upper end of the rod is attached to the horizontal arm by a bolt passing through one of the openings therein. The rod is urged downwardly by a compression spring 32 confined between washer 33 on its lower end and block 34 having a spherical seat in the arm. Arm 30 is preferably clamped to the post in such manner that it may be adjusted vertically to provide a simple adjustment for the spring. By attaching the rod to the lever at different holes, the effective tension of the spring may also be varied.

With the construction shown in Fig. 4, 15 the bell crank is mounted reversely to the one shown in Fig. 3. The bell crank, pivotally supported at 35, has a vertical arm 36 and a rearwardly extending arm 37. Depending from arm 37 is a link 38. Strapped or otherwise secured to the post is a lever arm 39 whose outer end is pivotally connected with a second lever 40. The inner end of lever 40 is in the form of a yoke, to partly encircle the post, and rests on a spring cap or washer 43 at the upper end of spring 44, embracing the post. The lower end of the spring preferably rests on an adjustable nut 45 on the post. The lower end

of link 38 is pivotally connected to lever 40. Consequently, the spring 44 always urges the 30 tong engaging arm toward vertical position, but, when the resistance of the tong becomes sufficiently great, the spring will yield to allow the post to move past the tong.

The various embodiments herein described 35 are merely illustrative of my invention, and various changes and modifications may be made in the construction thereof within the contemplation of my invention and within the scope of the appended claim.

I claim as my invention:

A make-up post for rotary well drilling apparatus comprising a post, a two-armed lever pivotally carried at the top of the post, one arm of said lever being a tong engaging 45 arm, means engaging the other arm for yieldably holding the tong engaging arm in a normal tong engaging position, said means including a spring, means for adjusting the effective action of the spring, and cushioning 50 means for cushioning the rebound movement of said lever when suddenly released from an abnormal position.

In testimony whereof I affix my signature.

EDGAR E. GREVE.
